WASHING MACHINE

Ivan Turner, Richmond, England

Application October 6, 1936, Serial No. 104,269
In Great Britain October 14, 1935

10 Claims. (Cl. 68—15)

This invention relates to domestic washing machines of the type in which the water contained in a tank or the like, in which the clothes are being washed, is agitated either by hand or mechanically. In the usual arrangements, the machine comprises a tank or container, with or without various rubbing abutments or corrugations on the sides, a central vertical spindle being adapted to carry an agitator of suitable form 5 which is immersed in the water and amongst the clothes.

These known arrangements possess certain drawbacks, particularly as regards the difficulty of providing proper bearings for the spindle, 15 straining of the clothes by lubricant, rust or so-called verdigris, and the interference of the underneath operating mechanism with devices for heating by gas or the like.

It is one object of the present invention to 20 avoid those disadvantages and at the same time to provide a simple, efficient and reliable washing machine intended for domestic use. Another object is to provide a turntable device between the tank and its support which device whilst 25 allowing the tank to be freely oscillated does not interfere with the heating of the tank from underneath.

I employ a tank or container arranged for oscillation on a vertical axis and provided with 30 agitator paddles or the like moving with the tank, the tank being mounted on an annular bearing track or turn-table with an open center, and a gas burner or other means for heating the water being placed beneath the bottom of 35 the tank and in the open center of the bearing track or turn-table.

Preferably the washing machine is provided 40 with means for power operation, a wringer or the like accommodated upon the washing machine being also driven by power from the same source when desired.

The invention is hereafter more fully described with reference to the accompanying drawings, in which:—

45 Fig. 1 is a part sectional elevation of the machine in the preferred embodiment.

Fig. 2 is a part side elevation showing the top cover in use as a rinsing bath.

Figs. 3 and 4 are details of a stand seen in 50 Fig. 2.

Fig. 5 shows the stand folded flat and hanging against the rear panel of the machine.

Fig. 6 is a detail in section on the line 6—6 of 55 Fig. 1, showing the mounting for the driving motor.

Fig. 7 is a section of the flexible coupling on the motor shaft.

Fig. 8 is an elevation of the reduction gearbox in vertical section on the axes of the shafts.

Fig. 9 is a longitudinal section and Fig. 10 a 5 transverse section of the reversing gearbox for driving the wringer.

Fig. 11 is a plan of a modified buffer device for the driving of the oscillating tank.

Fig. 12 is a vertical section on the line 12—12 10 of Fig. 11, on an enlarged scale.

Fig. 13 is a fragmentary view of a detail of construction showing the form of certain slots.

As shown in Figs. 1 and 2, the washing machine is constructed in the form of a cabinet, 15 made of pressed steel or the like, preferably finished in vitreous enamel, the cabinet being of rectangular shape, with four flat sides or panels 10, four legs 11 fitted with moulded rubber feet 12, and a top 13; the sides, legs and top are secured together by concealed bolts 14, and the legs are reinforced by angular metal straps 15 for supporting the heavy parts in the interior of the cabinet.

Carried approximately half-way down the 25 cabinet, and secured to the upper ends of the straps 15, is a pressed steel base-plate 16 forming a central bracing for the body of the cabinet and having a large circular opening of which the periphery is shaped to form a cup or ball-race 17, 30 fitted with caged balls 18. Upon this ball bearing there is rotatably mounted an annular pressed steel plate 19 forming a complementary ball race or cone 20, so that the two plates 16, 19 constitute a turn-table. The inner periphery of the 35 rotatable plate 19 is fitted with a number of safety catches 21 adapted to engage under the stationary ball race 17 to prevent the two plates from separating during normal operation. The upper flat portion 22 of the plate 19 has blocks 23 spaced 40 at intervals round its circumference and secured by bolts 24, the rim of the plate being flanged upwards at 25 outside these blocks, upon which there rests an open-topped cylindrical tank 26, constructed of sheet metal; the peripheral flange 45 25 of the plate 19 forms a guide to facilitate the centering of the tank thereon and to hold it in position during operation, but allowing the tank to be lifted completely out for cleaning, or for use as a separate boiler, or for other purposes. Additional guide arms 27 may also be provided as shown, these arms being engaged under the blocks 23 and secured by the same bolts 24.

The open top of the tank 26 has a flanged rim 28 doubled back inwards to provide a bead 29 55

upon which a domed lid 30 can rest, a handle 31 being provided for lifting and replacing the lid. The flanged rim 28 overhangs the top 13 of the cabinet, in which an opening is formed with a 5 beaded or flanged edge 32, leaving a clear passage round the tank and beneath the rim 28. The tank is provided internally with a plurality of vertical paddles or vanes 33, which as shown are integral with the arms of a spider 34 resting on 10 the bottom of the tank. The clothes placed in the tank for washing are therefore held away from the bottom of the tank by the paddles mounted on or near the bottom, and the clothes may be boiled while the agitation is taking place. 15 The spider 34 has its arms forked at their extremities to engage with radial driving lugs 35 of triangular shape, having integral flanges riveted or soldered to the walls of the tank. The spider 34 can thus be readily lifted out of place, leaving 20 a plain tank which can be used as an ordinary boiler when so desired, the spider being subsequently refitted by engaging its arms with the driving lugs 35.

If desired, the detachable lid 30 may be provided with paddles or stirrers as indicated at 25 36, consisting for example of non-rusting metal tubes closed at their lower ends; the lid 30 is arranged to fit sufficiently tightly in the bead 29 to prevent slip during the oscillation.

30 Beneath the tank and projecting into the central opening of the annular plate 19, there is mounted a gas burner 38, fed by a connection at 38¹, this burner being supported by a cross-bar 39 having its ends turned up and cranked outwards for attachment to the base-plate 16 as indicated in dotted lines at 40. A shallow tray 41 is provided beneath the burner in order to collect condensation water, the edges of this tray having a tight fit upon the turned-up ends 45 of the cross bar 39. The outer end of the burner tube 42 is also supported by a stay 43 secured to the periphery 44 of the base-plate 16, and is provided with the usual adjusting sleeve 45 for regulating the air supply to the burner; an oval opening 46 in the side panel 10 through which the gas-connection 38¹ extends, allows this sleeve to be adjusted, a similar opening or openings 47 being provided in one or more of the other panels 10 to allow of lighting and viewing the gas flame. The combustion gases pass between the 50 blocks 23 and upwards around the tank 26, emerging through the opening in the top 13 of the cabinet beneath the rim 28 of the tank.

The power unit comprises an electric motor 48 with vertical shaft 49 flexibly coupled to a 55 gearbox 50, which is mounted upon the base plate 16 over a second circular opening in the latter; one of the rear legs 11, with its reinforcing strap 15, forms in effect a bed-plate for the power 60 unit, the motor 48 being bolted to this leg over the lower end of the strap, while the base-plate 16 is bolted to all the four legs at the upper ends of the respective straps 15. As seen in Fig. 6, the motor 48 has a flat face 51 secured to 65 a bracket 52 shaped to engage the angular strap 15, a single bolt 53 holding the bracket 52 in place; thus the motor can easily be removed for inspection or repair, and a motor of any particular type or voltage can be fitted to suit the 70 available supply of current. The motor shaft 49 has its upper end formed with two opposite flat faces 54 whereby it has a readily detachable driving engagement with a moulded rubber coupling 55 which is similarly engaged with the 75 primary shaft 56 of the gearbox 50; the center

of the rubber coupling 55 is of substantially spherical form, with two cylindrical extensions 57 having metal ferrules thereon, these extensions being of oblong section internally so as to engage with the ends of the respective shafts 49 and 56, as seen in Fig. 7. The low-speed driven shaft 58 of the gearbox 50 carries at its lower end an external crank 59 driving a connecting rod 60 which transmits oscillatory motion to the rotatable plate 19 supporting the tank; buffer 10 springs are preferably arranged to cushion the shocks at the reversal of motion, this being done for example, as shown in Fig. 1, by providing a bridge 61 between two points on the inner periphery of the plate 19, and mounting a vertical 15 pin 62 thereon, the connecting rod 60 being attached to this pin 62 by a stirrup 63, with springs 64 inserted between the stirrup and the nuts 65 on the connecting rod. The shaft 58 is controlled axially by a rod 66 extending up through a guide 67 in the top 13 of the cabinet and provided with a knob 68 by means of which the shaft can be lifted so as to disengage the drive, as hereafter explained, the shaft being then retained in this disengaged position by turning 25 the knob 68 so that a cross-pin 69 rests on the upper edge of the guide 67; in order to re-engage the drive, the knob 68 is turned to drop the pin 69 into its notch 70 in guide 67.

A second low-speed driven shaft 71 extends up 30 from the gearbox 50, in axial alignment with the motor shaft 49, in order to drive an accessory such as a wringer 72, which is mounted above the top 13 of the cabinet; power is conveyed to the wringer through a gearbox 73 providing for reversal and interruption of the drive, and also allowing the wringer to be swung about a vertical axis in line with the shaft 71, the 35 wringer being supported from the gearbox 73 as hereafter described.

In the position shown in Figs. 1 and 2, the wringer 72 is adapted to operate on clothes lifted out of the tank 26, such clothes passing through the rollers 74 and being received at the back of the machine; as shown in Fig. 2, a rinsing bath 75 is provided into which the clothes are run, this bath being supported on a collapsible stand. The latter comprises two legs or uprights 76 each having a bearer 77 hinged thereto upon a bar 78 which forms a spacer between the uprights and a wooden block 80 attached thereto above the bar 78; a second spacer bar 79 is fitted between the lower ends of the uprights, the bath 75 being mounted on the bearers 77, between the blocks 80 and the back 55 of the cabinet. When in use, the stand is connected to the cabinet by hooking the free ends of the bearers 77 upon pegs 81 projecting from the rear panel 10, the bearers being provided with shoes 82 (see Figs. 3 and 4) suitably notched at 60 83 for connection to the pegs; when the stand is not required, the bearers are detached from the pegs 81 and folded down against the uprights 76, the folded stand being then turned round and mounted flat against the rear panel 65 10 (as shown in Fig. 5) by hooking on to the pegs 81 and also on to similar pegs 84 at a lower level, for which purpose keyhole slots 85 (as shown in Fig. 13) are formed in the uprights.

The bath 75 may be arranged to form a cover 70 for the cabinet when not in use, the bath being then inverted as indicated at 75¹ in Fig. 2; the wringer 72 is adapted to fold down flat on the top of the cabinet as indicated at 72¹ in Fig. 2, so as to fit inside the inverted bath.

The gearbox 50 is illustrated in Fig. 8, from which it can be seen that the primary shaft 56 carries a pinion 86 meshing with a large gear wheel 87 integral with a pinion 88 and rotatable upon a stud 89 mounted in the bottom of the box; the pinion 88 meshes on one side with a large gear wheel 90 having its hub 91 supported in a bearing 92 in the top of the gearbox, this hub providing a bearing for the driven shaft 58, while a second bearing 93 for that shaft is provided in the bottom of the gearbox, below which the shaft carries the crank 59. Driving connection between the gear wheel 90 and the shaft 58 is established by a clutch member 94, secured by a pin 95 to the shaft for engagement with dogs 96 on the hub 91; the control rod 66 carries a thimble 97, of which the collar 98 engages inside the clutch member 94 and above the end of the shaft 58, so that while the gear wheel 90 is rotating, the knob 68 of the control rod 66 can be operated to lift the shaft 58 and thereby disengage the clutch member 94 from the hub 91 of the wheel, the necessary axial movement of the driven shaft 58 being allowed by 25 clearance between the lower bearing 93 and the crank 59.

The pinion 88 also meshes with another large gear wheel 99 in axial alignment with the driving shaft 56, this gear wheel having its hub 100 supported in a bearing 101 in the top of the gearbox; the hub 100 is formed with dogs 102 engaging with a clutch member 103 secured upon the second low speed shaft 71 which drives the wringer 72 through the medium of the reversing gear-box 73. The shaft 71 is driven constantly so long as the motor 48 is running, the operation of the wringer being controlled by the gearbox 73, as hereafter described; the speed of this shaft 71, due to the reduction in the gearbox 50, may be for example 70 revolutions per minute with a motor speed of 1425 revolutions per minute, and the speed of the shaft 58 (when coupled by the clutch member 94) may also be 70 revolutions per minute. The several pinions and gear wheels are preferably immersed in oil contained in the gearbox, the top of the box being fitted in an oil-tight manner and secured by studs 104; a detachable cap 105 is provided on the top, over the stud 89, for refilling the gearbox with oil when necessary.

The reversing gearbox 73 is illustrated in Figs. 9 and 10, from which it can be seen that the cabinet top 13 is fitted with a spigot member 106 upon which the box 73 is mounted, the member 106 being secured by bolts 107 passing through an annular washer plate 108 on the inside of the cabinet. The gear box 73 comprises a base 109 to which the upper part of the box is hinged upon a pivot 110 along one side, the base having along its opposite side a vertical flange 111 through which a locking screw 112 with conical point 113 enters a hole 114 in the corresponding side of the gearbox, so as to hold the latter rigid with the base 109; the latter is provided with a vertical socket 115 surrounding the spigot member 106, the socket being split radially at 116 and provided with a clamping screw 117 operated by a lever or handle 118, whereby the socket can be clamped in relation to the spigot.

The low-speed shaft 71 for driving the wringer has its upper end formed with two opposite flat faces 119; this end of the shaft passes up through the annular plate 108 and through a hole 120 in the cabinet top 13 into the interior

of the spigot member 106, which forms a bearing for a bevel pinion 121 having the bore of its hub 122 shaped to engage the flat faces 119 on the shaft 71. The pinion 121 is adapted to mesh with one or the other of two bevel wheels 123, 124, slidably mounted upon a horizontal shaft 125 in the upper part of the gearbox 73; one end of this shaft is reduced at 126 to take a bearing in a boss 127 in one of the ends of the box, while the other end of the shaft is formed with two opposite flat faces 128 and is engaged in a correspondingly shaped hole 129 in a bushing 130 rotatably journaled in the other end of the gearbox. The two bevel wheels 123, 124 are fitted with a single key 131, slideable along a keyway 132 in the shaft, and they are connected together as regards axial motion by a bridge piece 133 having two parallel semi-circular ribs 134, which engage in two circumferential grooves 135, one on each wheel; the flat top 136 of the bridge piece 133 is slotted at 137 and is engaged by a gear-shift crank 138 with an eccentric or crank pin 139 entering the slot 137. The vertical spindle 140 of this shift-crank is rotatably mounted in a boss 141 at the top of the gearbox, its projecting end 142 being squared and fitted with a lever or handle 143, retained by a screw 144 and washer 145. The boss 146 of the lever 143 is formed with teeth 147 engaging with a stop-pin 148 to one side of the boss 141 in order to limit the turning movement of the handle; a latching ball 149, backed by a spring 150, is mounted in a hole 151 in the boss 141, the inner face of the lever boss 146 being formed with shallow pits 152 for engagement by the latching ball 149 in definite positions of the handle 143. In Fig. 9, the two bevel wheels 123, 124 are out of mesh with the pinion 121 upon the shaft 71; this neutral position represents the middle position of the lever handle 143; by turning the latter in one direction or the other, one or other of the bevel wheels 123, 124 can be brought into mesh with the pinion 121, so as to drive the shaft 125 and bush 130 in the forward or in the reverse direction, the movement of the spindle 140 being communicated by the eccentric pin 139 to the bridge piece 133 which shifts the bevel gears 123, 124 accordingly.

At the end supporting the bush 130, the gearbox 73 is provided with a vertical web 153 against which a pair of bracket plates 154 are secured by bolts 155, these brackets being arranged to carry the wringer 72 with one of its rollers 74 in line with the driven shaft 125; the spindle 156 of this roller is extended into the bush 130, the end of the spindle being formed with two opposite flat faces 157 for taking the drive. Upon releasing the clamping lever 118, the spigot mounting of the gearbox 73 allows the latter to be revolved about the axis of the vertical shaft 71, together with the wringer 72, so that the latter can be brought to a position for use between the washing tank 26 and rinsing bath 75, or to a position at right angles thereto for use between the rinsing bath and a table or basket; in each of these positions the reversing gearbox enables the wringer to be driven in either direction or to be stopped at will. The wringer may be provided with a quick-release device by mounting the pressure screw 158 upon a trunnion 159 so that by knocking the screw aside the pressure can be released instantly from the rollers 74 in case of emergency.

When the wringer is out of operation, it may be folded down over the top of the cabinet, after

releasing the locking screw 112, which allows the upper part of the gearbox 73, together with the wringer 72, brackets 154, shaft 125 and bevel gears 123, 124, to turn about the pivot 110 into the position indicated at 721 in Fig. 2; the pinion 121 will then revolve idly in its bearing so long as power is transmitted by the shaft 71 from the reducing gearbox 50.

Alternatively, the wringer 72 may be kept in operation with the tank driving mechanism out of action, for example when the clothes are being passed through the wringer after the final rinsing; in such a case the gearbox 50 will have its clutch member 94 disengaged so that the crank 15 59 remains stationary, but the second low-speed shaft 71 will continue to transmit power to the reversing gearbox 73 for the operation of the wringer.

Similarly the second low-speed shaft 71 may be continued in motion, when the tank driving mechanism is out of action, in cases where the wringer is replaced by an ironing roller or other device, arranged to be driven by the same vertical shaft 71; by releasing the clamping lever 25 118, it is possible to lift the reversing gearbox 73, together with the brackets 154 and wringer 72, after which the ironing or other device can be mounted upon the spigot member 106, being clamped thereon and driven by the shaft 71 30 in a similar manner to that already described in the case of the wringer and its gearbox.

By disconnecting the clutch member 94 and placing the gearbox 73 in the neutral position by means of the handle 143 it is possible to run the motor 48 idly when desired.

Fig. 11 shows the connecting rod 60 driven by the crank 59 below the gearbox 50, with its other end attached by a pin 178 to a double bell-crank lever 179 mounted on a pivot 180 on the inner periphery of the plate 19, the oppositely extending arms 181 of the lever being engaged by buffer springs 182 supported by brackets 183 bolted or otherwise secured to the underside of the plate 19, which is rotatably mounted on caged balls 45 18 running in the cup or ball-race 17 as previously described. In the position shown in Fig. 11, with the connecting rod 60 in mid-stroke, the pin 178 lies on the same radial line as the pivot 180 with respect to the plate 19, but towards each end of the oscillatory movement, when the crank 59 is 50 on a dead center, the plate 19 supporting the tank 26 tends to outrun the connecting rod 60, one or other of the springs 182 becoming compressed as the lever 179 rocks upon its pivot 180 to allow for 55 the overrun of the plate 19. Thus the buffer device provides for cushioning the shocks at the reversal of motion of the tank 26, and also allows the tank a greater amplitude of motion than is determined by the crank 59 and connecting 60 rod 60.

What I claim is:—

1. A washing machine comprising a tank, a turntable having an open center, said tank being mounted for oscillation on said turntable, and means for oscillating said tank, said oscillating means including a member connected to the movable part of said turntable by way of a pivot located within said open center but eccentric to the axis of said turntable.

70 2. A washing machine comprising a circular tank, a horizontal turntable including fixed and movable parts with interposed bearing means, said fixed and movable parts being of annular form and affording an open center for said turntable, said tank being mounted upon said mov-

able part and adapted for oscillation in relation to said fixed part, a pivot member secured to said movable part, said pivot member having a vertical pivotal axis located within said open center but eccentric thereto, and a driving connection to said pivot member.

3. A washing machine comprising a tank, said tank having a substantially flat bottom and being provided internally with agitating means, a turntable having an open center, said tank being mounted on said turntable for oscillation around a vertical axis, means for heating said tank, said heating means being placed beneath the flat bottom of said tank and within the open center of said turntable, and means for oscillating said tank, said oscillating means including a pivot member secured to a movable part of said turntable, said pivot member having its pivotal axis located within said open center but eccentric thereto, and a driving connection to said pivot member.

4. A washing machine comprising a tank, said tank having a substantially flat bottom and being provided internally with agitating means, a turntable having an open center, said tank being mounted on said turntable for oscillation around a vertical axis, means for heating said tank, said heating means being placed centrally beneath the flat bottom of said tank, and means for oscillating said tank, said oscillating means including a pivot member secured to a movable part of said turntable, said pivot member having its pivotal axis located within said open center at a radial distance from the vertical axis of said turntable and clear of said heating means, and a driving connection to said pivot member.

5. A washing machine comprising a circular tank, a horizontal turntable including fixed and movable parts with interposed bearing means, said fixed and movable parts being of annular form and affording an open center for said turntable, said tank being mounted upon said movable part and adapted for oscillation in relation to said fixed part, a gas burner for heating said tank, said gas burner located in said open center, a pivot member secured to said movable part, said pivot member having a vertical pivotal axis located within said open center at a radial distance from the vertical axis of said turntable and clear of said gas burner, and a driving connection to said pivot member.

6. A washing machine comprising a circular tank, a horizontal turntable including fixed and movable parts with interposed bearing means, said fixed and movable parts being of annular form and affording an open center for said turntable, said tank being mounted upon said movable part and adapted for oscillation in relation to said fixed part, a pivot member secured to said movable part, said pivot member having a vertical pivotal axis located within said open center but eccentric thereto, a driving connection to said pivot member, a gas burner for heating said tank, said gas burner located within said open center and inside the arcuate path of said pivot member secured to said movable part, and a tube supplying said gas burner, said tube extending clear of said driving connection below said turntable.

7. A washing machine, comprising a sheet-metal cabinet, a horizontally disposed metal plate forming a central bracing for said cabinet, said metal plate having an opening of circular form, the periphery of said opening forming the fixed part of an annular turntable having an open

center, a movable part of annular shape supported on said fixed part to constitute said turntable, a tank mounted upon said movable part, a pivot member secured to said movable part, said pivot member having a vertical pivotal axis located within said open center but eccentric thereto, and a driving connection to said pivot member, said driving connection being below said metal plate.

5 8. A washing machine, comprising a sheet-metal cabinet, a horizontally disposed metal plate forming a central bracing for said cabinet, a driving motor mounted below said plate, a cylindrical tank mounted above said plate, said tank adapted for oscillation on a vertical axis, an annular turntable for said tank, the fixed member of said turntable being formed by an apertured portion of said metal plate, the movable member of said turntable being of approximately the same diameter as said tank but having an open center, a pivot member secured to said movable member, said pivot member having a vertical pivotal axis located within said open center but eccentric thereto, and below said plate, and connections from said driving motor to said pivot member.

10 9. A washing machine, comprising a sheet-metal cabinet, a horizontally disposed metal plate forming a central bracing for said cabinet, a driving motor mounted below said plate, a cylindrical tank mounted above said plate, said tank adapted

for oscillation on a vertical axis, an annular turntable for said tank, the fixed member of said turntable being formed by an apertured portion of said metal plate, the movable member of said turntable being of approximately the same diameter as said tank but having an open center, a gas burner for heating said tank, said gas burner being located within said open center, a tube supplying said gas burner, said tube extending below said plate and to the exterior of said cabinet, a pivot member secured to said movable member, said pivot member having a vertical pivotal axis located within said open center and inside the arcuate path of said pivot member and below said plate, and a connecting rod transmitting power from said driving motor to said pivotal member, said connecting rod being below said plate and clear of said gas burner and supplying tube.

15 10. A washing machine comprising a tank arranged for oscillation on a vertical axis, agitator paddles in the interior of said tank, an annular turntable supporting said tank, said turntable having an open center, a gas-burner for heating said tank, said gas burner being arranged beneath the bottom of said tank and in the open center of said turntable, a connecting rod for oscillating said tank, and a pivotal attachment for said connecting rod upon the inner periphery of the rotary member of said turntable.
